FACE SHIELD FOR A SAFETY HELMET

Christian Zahn, Braunschweig, Germany, assignor to
Schuberth-Werk K.G., Braunschweig, Germany

Filed Nov. 3, 1966, Ser. No. 4,540

Term of patent 14 years

(Cl. D2—233)

FIG. 1

FIG. 2

FIG. 3

FIG. 1 is a side elevational view of a face shield for a helmet showing my new design;

FIG. 2 is a front elevational view thereof; and

FIG. 3 is a side perspective view thereof.

The essential features of my design reside in the portions shown in full lines on the drawings.

I claim:

The ornamental design for a face shield for a safety helmet, substantially as shown and described.
